DISPLAY RACK

Orval L. Greenman, Grand Rapids, and Robert J. Stewart, Comstock Park, Mich., assignors to The Bulman Corporation, Grand Rapids, Mich., a corporation of Michigan

Application November 19, 1958, Serial No. 53,447

Term of patent 14 years

(Cl. D80—9)

I claim:

The ornamental design for a display rack, as shown.
